(57) **CLAIM**

The ornamental design for a patterned glove with a flared cuff, as shown and described.

DESCRIPTION

FIG. 1 is a front elevation view of the patterned glove with a flared cuff in accordance with our design, wherein the glove is for a left hand; and the front elevation view of the glove for the right hand, which is not shown herein, is a mirror image thereof;

FIG. 2 is a rear elevation view of the glove of FIG. 1, wherein the rear elevation view of the glove for the right hand, which is not shown herein, is a mirror image thereof; FIG. 3 is a left side elevation view of the glove of FIG. 1, wherein the left side elevation view of the glove for the right hand, which is not shown herein, is a mirror image thereof; FIG. 4 is a right side elevation view of the glove of FIG. 1, wherein the right side elevation view of the glove for the right hand, which is not shown herein, is a mirror image thereof;

FIG. 5 is a top plan view of the glove of FIG. 1, wherein the top plan view of the glove for the right hand, which is not shown herein, is a mirror image thereof;

FIG. 6 is an enlarged view of the highlighted region of FIG. 1, showing a pattern that is provided on the gripping surfaces of the glove; and,

FIG. 7 is an enlarged cross-section of the pattern shown in FIG. 6.

The broken lines in the drawings show the environment in which the design is used. The broken lines form no part of the claimed design.

The dot-dot-dash lines show the boundary of the highlighted region of FIG. 1 and form no part of the claimed design.
